UNITED STATES PATENT OFFICE.

ROBERT G. LE TOURNEAU, OF STOCKTON, CALIFORNIA.

SCARIFIER.

Application filed June 2, 1926. Serial No. 113,164.

This invention relates to improvements in scarifiers such as are used in connection with road making or repairing operations, and particularly to the mounting and securing of the teeth onto the scarifier frame.

Such teeth due to the hard wear to which they are subjected frequently require replacing either because of their being worn out or from having been broken. At present as far as I am aware all such teeth are mounted on their frame by bolting in different manners. The bolt-nuts sometimes freeze so that it is almost impossible to get the same off, and yet if they are not tightly 10 cinched up the slippage of the teeth is permitted, and at times the bolt or tooth breaks. In any event considerable time and effort is necessary to effect tooth-changes, as is well known to all those operating devices of this 15 character.

The principal object of my invention therefore is to provide means for mounting such teeth to their frame in such a manner that they are positively held against upward and downward movement, while at the same time the teeth may be almost instantly removed whenever necessary. The bolts with their objectionable features are eliminated, and the teeth are not weakened in 20 any manner so that there is no tendency for the same to fracture under any load. Also the holding means is so arranged that the strain on the teeth does not tend to distort or break such means.

30 A further object of the invention is to produce a simple and inexpensive device and yet one which will be exceedingly effective for the purpose for which it is designed.

These objects I accomplish by means of 40 such structure and relative arrangement of parts as will fully appear by a perusal of the following specification and claims.

In the drawings similar characters of reference indicate corresponding parts in the several views:

Fig. 1 is a sectional elevation of my improved scarifier tooth and frame mounting structure.

50 Fig. 2 is a fragmentary section showing a modified form of structure.

Referring now more particularly to the characters of reference on the drawings, and particularly at present to Fig. 1, A denotes a transverse beam which is mounted on the rear end of a longitudinal frame B of suitable character, the particular design or

set-up of the implement as a whole forming no part of my invention.

The beam A preferably comprises a hollow box section member consisting of top and bottom plates 1 and 2, and end plates 3; all said plates being welded together along their edges to form a rigid structure.

Each tooth to be mounted in connection with this beam comprises a ground engaging portion 4 of suitable shape and a shank 5. The back face of the shank toward this upper end is beveled as at 6 with a head or lug 7 at the top overhanging the forward face of the shank. This tapered portion is 70 adapted to seat in vertically aligned orifices 8 and 9 cut through the plates 1 and 2 respectively, the upper orifice being narrower than the lower to correspond somewhat to the reduced size of the upper end of the 75 shank.

The lower orifice 9 is of such a size as to snugly receive the shank just below the taper portion thereof, in which position of the shank the head 7 rests on top of the 80 beam. It will therefore be seen that the tooth can neither move up nor down to any extent. In order to enable the head to be cleared from the beam so that it can pass through the upper orifice 8 when it is desired to remove the tooth, said upper orifice is made sufficiently deeper or longer than the adjacent portion of the shank so that the latter may be tilted longitudinally sufficient for the head to pass through the orifice 85 as shown by the dotted line position in the drawing. To normally prevent the shaft from having such tilting movement I provide a drift key 10 to be removably inserted into the orifice 8 between the rear edge of 90 the same and the adjacent face of the shank. With this arrangement it will be seen that the working strain on the tooth is taken by the forward edge of the upper orifice and by the rear edge of the lower orifice. There is therefore no tendency for the key to be forced out of place or to be distorted by pressure, but it will tend rather to lodge 100 in place all the more firmly.

The length of the beam is sufficient to 105 enable any desired number of teeth to be mounted thereon, while the width of the beam is such as to allow two rows of teeth being supported. While the holes for such rows are shown in the drawing as being in common longitudinally alignment relative to the line of travel of the implement, these 110

holes would actually be staggered or offset, since it will be obvious that one tooth directly behind another would not be of any value.

5 It will also be obvious that as far as the principle of construction and operation of my arrangement is concerned the beam could be made solid, but such construction would render the same so heavy as to be impracticable.

10 The key is straight, and is held in place by gravity, so that it may be removed by hand without the use of any tools. A short length of chain 11 preferably connects the key to the main frame to prevent possible loss of the key.

15 In the type of device shown in Fig. 2, the taper portion 6^a of the shank 5^a extends below the orifice 9^a, and the shank therefore wedges into the orifice. Otherwise the arrangement of parts is the same.

20 From the foregoing description it will be readily seen that I have produced such a device as substantially fulfills the objects of the invention as set forth herein.

25 While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to 30 secure by Letters Patent is:

35 1. In a scarifier, a horizontal beam hav-

ing a vertical opening therethrough smaller at the top thereof than at the bottom, a tooth having a shank insertible through the opening from the bottom thereof, the shank 40 snugly fitting the opening at the bottom, but being narrower at its upper end than the adjacent end of the opening, an overhanging head on the shank disposed to overhang the beam at one end of the relatively 45 wider portion of the opening, whereby when the shank is tilted in the opening the head may pass therethrough, and means between the shank and opening for normally preventing such tilting movement.

50 2. A structure as in claim 1, said means comprising a removable drift to be inserted in the upper end of the opening between the face of the shank opposite to the head and the adjacent end of the opening.

55 3. In a scarifier, a horizontal beam having a vertical opening therethrough, a tooth having a shank insertible through the opening from the bottom thereof, the rear face of the shank being tapered in a manner to 60 cause the shank to wedgingly engage the lower end of the opening but to leave a space between the rear end of the opening at its top and the adjacent tapered face of the shank, a head on the shank overhanging 65 the forward face of the same to overhang the top of the beam, and a removable draft insertible in the space at the upper end of the opening.

In testimony whereof I affix my signature.

ROBERT G. LE TOURNEAU.
